SUPERHEATER BOILER

John A. Barnes, Chappaqua, N. Y., assignor to
The Superheater Company, New York, N. Y.

Application July 22, 1936, Serial No. 91,823

16 Claims. (Cl. 122—235)

The present invention relates to boilers and particularly to boilers provided with superheaters.

A feature of the present invention resides in an improved boiler construction affording protection to the superheater thereof when the boiler is being fired up.

A second feature consists of a novel method of regulating the temperature of superheated steam obtained from the boiler.

Other features and advantages of the invention will become apparent upon consideration of the following description and appended claims when read in conjunction with the accompanying drawings showing several illustrative embodiments of the invention.

In the drawings:

Fig. 1 is a diagrammatic elevational view, partly in section, of one form of boiler construction embodying the present invention.

Figs. 2, 3 and 5 are similar elevational views showing other boiler constructions in which the invention is embodied.

Fig. 4 is a sectional view, partly broken away, of the boiler illustrated in Fig. 5, and

Fig. 6 is a sectional view on the line 6—6 in Fig. 5 showing the arrangement of the tubes of the boiler illustrated in Figs. 4 and 5.

In the boiler shown in Fig. 1, the steam and water drum 10 extends across the upper part of one side of the boiler and is connected to the water drum 11 disposed therebelow by a bank 12 of generating tubes consisting of a plurality of rows of vertically disposed tubes. A pair of headers 13 and 14 extend across the opposite side of the boiler in positions vertically intermediate the drums 10 and 11. Headers 13 and 14 are connected to steam drum 10 by rows of tubes 15 and 16, respectively, and to water drum 11 by rows of tubes 17 and 18, respectively. Header 14 is also connected to drum 11 by one or more rows of tubes 19.

The sides of the boiler are provided with water walls consisting of tubes 25 connected between upper and lower headers 26, 27, which in turn are connected to drums 10 and 11 by circulating tubes 28. The tubes 16, 18 and side walls tubes 25 define a furnace space at one side of the drums 10, 11.

The tubes 15 and 19 have portions extending substantially horizontally across the furnace space at one side of the drums 10 and 11 to divide the furnace space to form a pair of furnace chambers, a main chamber 20 and an auxiliary chamber 21, to which fuel is introduced by burners 22 and 23 individual to the respective cham-

bers. The horizontally disposed portions of the tubes 15 are spaced vertically from the corresponding portions of the tubes 19 to provide room for accommodating the heat absorbing elements of a superheater 24.

The tubes of the innermost row in bank 12 have their lower portions 12a in contact to form a baffle precluding the flow of gases directly from the main furnace chamber 21 through the tube bank 12. The upper portions 12b of alternate tubes in the innermost row are offset from the plane of the remaining tubes to provide openings placing the auxiliary furnace chamber 20 in communication with the tube bank 12 and at least the horizontally disposed portions of the tubes 15 and 19 also, are spaced so that the combustion gases may flow from the lower chamber 21 across superheater 24 to the upper chamber 20 and mingling with the gases therein flow therefrom through the tube bank 12.

The boiler construction illustrated in Fig. 2 is quite similar to that shown in Fig. 1. However, the rows of tubes 35 and 36 connected to steam drum 10 and defining opposite walls and the bottom and top of the upper furnace chamber 20 are all connected into header 13. Header 13 is in turn connected to drums 10 and 11 by circulator tubes 37, 38 located exteriorly of the furnace chambers. The other intermediate header 14 is connected to steam drum 10 by rows of tubes 39. In this arrangement the inclined portions of the tubes 35 and 39 extending from headers 13, 14 divide the furnace space into upper and lower chambers 20, 21 and are spaced vertically to accommodate the superheater 24.

In the boiler of Figure 3, a header 43 which extends across the lower portion of the boiler in a position intermediate the water drum 11 and the opposite side of the boiler is connected to the steam drum 10 by rows of bent tubes 40 and 41. These tubes have vertically disposed portions arranged opposite bank 12 and divide the furnace space, defined by water walls 25 and bent tubes 46 connected to drum 10, into two furnace chambers 20 and 21. These rows of tubes 45 also are spaced to accommodate the superheater 24 therebetween. Header 43 is connected to drum 11 by circulating tubes 44 and by tubes 45 to a header 47, extending along the lower portion of the wall opposite the drum 11. The contacting lower portions 12a of the innermost row of tubes in bank 12 prevent the direct flow of gases from the lower part of chamber 20 through the bank and the upper portions 12b of alternate tubes in this row are offset to place the upper part of

chamber 20 in communication with the bank 12. Chamber 21 is placed in communication with the chamber 20, so that combustion gases flow across superheater 24 thereto, by spacing at least the

5 vertical portions of the rows of tubes 40 and 41.

In the construction shown in Figs. 4 to 6, the two furnace chambers 20 and 21 are formed by rows of tubes 50 and 51 connected into upper and lower headers 52 and 53, respectively, disposed 10 normally with respect to the drums 10 and 11 intermediate the ends thereof. These headers are connected to drums 10, 11 by tubes 54, 55. The rows of tubes 50 and 51 also are spaced to accommodate a superheater 24 and the lower 15 header 53 to which they are connected receives water from drum 11 through tubes 55. The wall of furnace chambers 20 and 21 which is opposite drums 10 and 11 and also the roof of these chambers are formed by a row of bent tubes 56 connected 20 between drum 10 and a header 57 connected in turn to drum 11 by a row of tubes 59 defining the bottom of the furnace chambers. As shown in Fig. 6, the tubes 12c of the innermost row of bank 12, which form the wall of chamber 25 21 opposite that in which burners 23 are located, are arranged in contact with each other. Thus, combustion gases are caused to flow laterally through the rows of tubes 50 and 51 in passing over the superheater 24 to the chamber 20 30 from which they pass to the bank 12 between the spaced tubes 12d of the innermost row.

In the operation of the several somewhat different arrangements shown in the drawings, firing up is effected by means of the burners 22 for 35 the chamber 20 and the superheater 24 is screened from the flames therein by rows of tubes 15, 35, 40 and 51, (Figs. 1, 2, 3 and 4, respectively). When pressure has been raised in the boiler, the burners 23 are placed in operation, and the burners 22 may be shut down or operated at less than 40 their full capacity. As a result, the superheater is effectively protected during firing up inasmuch as it is not exposed to high temperature gases before the supply of steam is adequate to afford 45 protection.

Regulation of the temperature of superheated steam obtained from the superheaters 24 may be effected by burning the greater part of the fuel required to maintain a determined load in the 50 chambers 21 from which the gases of combustion pass across the superheater 24 and through the furnace chamber 20 to the tube bank 12. The remainder of the fuel required is burned in the chambers 20 and passes to the tubes of the bank 55 12 without contacting the superheater 24. In the event that the superheat is too low, the relative proportions of the total amount of fuel burned in chambers 20 and 21 may be varied so as to increase the proportion burned in chamber 60 21 and decrease that burned in chamber 20 with the result that the temperature of the superheated steam is raised since the volume of gases flowing over the superheater is increased. Conversely, when the temperature of the superheated 65 steam is too high the burners for the chamber 21 may be operated at a lower rate and the rate for the burners for chamber 20 may be increased, thus lowering the temperature of the superheated steam because combustion gases from 70 chamber 20 in which the firing rate has been increased do not pass over the superheater 24.

Although several illustrative embodiments of the invention have been described herein, it is to be understood that there are many changes and 75 variations which may be made without departing

from the spirit of the invention and therefore it is intended to include all such changes and variations within the scope of the following claims.

What I claim is:

1. In a boiler having upper and lower drums interconnected by a bank of generating tubes; means defining a furnace space at one side of said bank; generating tubes connected into the circulation system of the boiler and having at least portions thereof arranged in spaced rows dividing said furnace space to form separate furnace chambers, the tubes of said rows being spaced so that one chamber communicates with the other; means precluding the direct flow of gas from said one chamber to said bank; fuel feeding means individual to said chambers; and a superheater having the heat absorbing element disposed between said tube rows and exposed to combustion gases flowing from said one chamber among said tubes and through said other chamber to said bank. 15

2. In a boiler having upper and lower drums interconnected by a bank of generating tubes; means defining a furnace space at one side of said bank; spaced generating tubes connected into the 25 boiler circulation system and having portions thereof arranged in a row extending through said furnace space at a level intermediate said drums to divide it into communicating upper and lower furnace chambers, the upper chamber communicating with the lower and with said generating bank; means precluding the direct flow of gases from said lower chamber to said bank; separate firing means for said chambers; and a superheater having the heat absorbing elements there- 30 of located between said chambers at one side of said row of tubes and contacted by combustion gases flowing from said lower chamber through said upper chamber to said bank.

3. In a boiler having upper and lower drums 40 interconnected by a bank of generating tubes; means defining a furnace space at one side of said bank; tubes connected into the boiler circulation system and having portions arranged in spaced rows extending through said space at 45 levels intermediate said drums to divide it into upper and lower furnace chambers, said portions of the tubes of said rows being spaced to place said lower chamber in communication with said upper chamber; means precluding the direct flow 50 of gases from said lower chamber to said bank; separate fuel feeding means for said chambers; and a superheater having the heat absorbing elements thereof disposed between the rows formed by said tube portions. 55

4. In a boiler having upper and lower drums interconnected by a bank of generating tubes; means defining a furnace space at one side of said bank; a header positioned opposite and vertically 60 intermediate said drums; spaced generating tubes connected between said header and said upper drum and having portions arranged in a row dividing said space to form upper and lower furnace chambers, said upper chamber communicating with the lower and with said tube bank; means precluding the direct flow of gases from 65 said lower chamber to said bank; separate means for introducing fuel to said chambers; a superheater having the heat absorbing elements 70 thereof extending beneath said row of generating tubes; other generating tubes connected to one of said drums and having portions arranged in a row extending between said superheater elements and said lower furnace chamber; and 75

- means completing the connection of said other tubes to the circulation system of the boiler.
5. A boiler as recited in claim 2 characterized in that portions of said tubes adjacent said chamber defining portions thereof extend angularly with respect to the latter and constitute the side of said upper chamber adjacent said bank.
6. A boiler as recited in claim 2 characterized in that portions of said tubes adjacent said chamber defining portions thereof extend angularly with respect to the latter and constitute the side of said upper chamber adjacent said bank; and other oppositely bent tubes having portions constituting the top and bottom of said upper and lower chambers, respectively, and the sides of said chambers opposite said bank.
7. A boiler as recited in claim 2 characterized in that portions of said tubes adjacent said chamber defining portions thereof extend angularly with respect to the latter and constitute corresponding sides of said chambers located adjacent said bank.
8. In a boiler having upper and lower drums interconnected by a bank of generating tubes; means defining a furnace space at one side of said bank; a pair of headers extending across the side of the boiler opposite said bank in positions vertically intermediate said drums; spaced tubes having portions arranged in rows extending across said furnace space to divide it into communicating, upper and lower furnace chambers, the tubes that form one row connecting said upper drum to one header of said pair and the tubes that form an adjacent row connecting the other header to said lower drum with said tube portions of said one row spaced from the corresponding portions in said adjacent row to accommodate a superheater; separate fuel feeding means for each of said chambers; means precluding the direct flow of gases from said lower chamber to said bank; tubes connecting said one header to said lower drum; and tubes connecting said other header to said upper drum.
9. In a boiler having upper and lower drums interconnected by a bank of generating tubes; means defining a furnace space at one side of said bank; spaced generating tubes connected into the boiler circulation system and having at least portions thereof arranged in spaced vertical rows dividing said space to form separate furnace chambers one of which communicates with the other, while only the latter communicates directly with said bank; a superheater having the heat absorbing elements thereof disposed between said rows and exposed to combustion gases flowing from said one chamber among said tubes and through said other chamber to said bank; and fuel feeding means individual to said chambers.
10. In a boiler having upper and lower drums interconnected by a bank of generating tubes; means defining a furnace space at one side of said bank; spaced generating tubes connected into the circulation system of the boiler and having portions extending in rows opposite said bank and dividing said space to form separate furnace chambers one of which communicates with the other and also with said bank, said rows of tubes being spaced to accommodate a superheater; a superheater between said rows of tubes; and fuel feeding means individual to each of said chambers.
11. A boiler as recited in claim 10 wherein the upper and lower ends of said rows of tubes connect respectively into the upper drum and a header that is positioned opposite said lower drum and which is connected thereto by circulating tubes.
12. In a boiler having upper and lower drums interconnected by a bank of generating tubes; means defining a furnace space at one side of said bank; spaced generating tubes connected into the circulating system of the boiler arranged in spaced rows intermediate the ends of said drums and normal to the longitudinal axes thereof for dividing said space to form separate furnace chambers one of which communicates with the other and also with said generating bank; a superheater having the heat absorbing elements thereof disposed between said rows of tubes and exposed to combustion gases flowing from said other chamber and between said tubes through said one chamber to said bank; and fuel feeding means individual to said chambers.
13. A boiler as recited in claim 12 characterized in that said rows of tubes are connected into headers disposed normally to the longitudinal axes of said drums and connected into the circulation system of the boiler.
14. In a boiler having upper and lower drums, interconnected by a bank of generating tubes; means defining a furnace space at one side of said bank; a pair of headers positioned vertically intermediate said drums and opposite said bank; spaced generating tubes connected to said upper drum and having portions arranged in rows extending through said furnace space for dividing it into communicating upper and lower furnace chambers, the tubes that have portions forming one row being connected to one header of said pair with said tube portions spaced from corresponding portions of tubes that form another row and which are connected to the other header; separate fuel feeding means for said chambers; means precluding the direct flow of gases from said lower chamber to said bank; a superheater having the heat absorbing elements thereof disposed between said portions of said tubes and heated by gases from said lower chamber; and other tubes completing the connection of said headers to the circulation system of the boiler.
15. In a boiler; a pair of superposed drums; means defining a furnace space at one side of said drums; a bank of generating tubes interconnecting said drums and having a plurality of adjacent tubes of its innermost row contacting each other to preclude the flow of combustion gases therebetween and the remaining tubes spaced to permit such flow; spaced generating tubes connected into the circulation system of the boiler and having at least portions thereof arranged in a row dividing said furnace space to form separate furnace chambers, one chamber communicating with said generating bank through the spaced tubes of the innermost row thereof and the other chamber being cut off from direct communication with said bank by the contacting tubes of said bank row; fuel feeding means individual to said chambers; and a superheater having the heat absorbing elements thereof disposed at one side of said row of furnace dividing tubes and exposed to combustion gases from said other chamber only.
16. In a boiler having upper and lower drums interconnected by a bank of generating tubes; means defining a furnace space at one side of said bank; generating tubes connected into the boiler circulation system and having at least portions thereof arranged in a row dividing said space to form a main furnace chamber and an auxiliary furnace chamber, said tubes being

spaced so that one chamber communicates with the other; a flue arranged to receive gases passing from said auxiliary furnace chamber over said bank; baffle means precluding the direct flow of gases from said main furnace chamber to said bank; fuel feeding means individual to said furnace chambers; and a superheater having the

heat absorbing elements thereof disposed at one side of said row of tubes and exposed to combustion gases flowing from said main chamber between said tubes, through said auxiliary furnace chamber and across said bank to said flue. 5

JOHN A. BARNES.
